UNITED STATES PATENT OFFICE.

DAVID F. GREENAWALT, OF YORK, PENNSYLVANIA.

MERCHANDISE-HOLDER.

No. 872,411.

Specification of Letters Patent.

Patented Dec. 3, 1907.

Application filed October 25, 1906. Serial No. 340,583.

To all whom it may concern:

Be it known that I, DAVID F. GREENAWALT, a citizen of the United States, residing at York, in the county of York and State of Pennsylvania, have invented a new and useful Merchandise-Holder, of which the following is a specification.

The principal object of the present invention is to provide a protecting case or holder 10 for the reception of rolls of silk or other articles of merchandise, the case or holder being so arranged as to protect the contents by precluding the entrance of dust or dirt, by excluding moisture and light, and, when the 15 article is in roll form, preventing the formation of wrinkles.

A further object of the invention is to provide a merchandise holder in the form of a case made of sheet material or the like which 20 may be rolled, lapped or folded for the purpose of accommodating rolls of articles of any diameter and which may be contracted as the size of the roll or other article is gradually decreased through sales.

25 A still further object of the invention is to provide a flexible case or holder which may be secured in position at any convenient point, either on a wall, counter, table, rack or within a suitable casing as desired.

30 A still further object of the invention is to provide a casing or holder formed of relatively stiff material adapted especially for containing rolled silk or other fabric, and which may serve not only as a means for 35 closing and protecting the fabric, but will, also, hold the same smooth and free from wrinkles.

With these and other objects in view, as will more fully hereinafter appear, the invention 40 consists in certain novel features of construction and arrangement of parts, herein- after fully described, illustrated in the accompanying drawings, and particularly pointed out in the appended claims, it being understood that various changes in the form, proportions, size and minor details of the structure may be made without departing from the spirit or sacrificing any of the advantages of the invention.

50 In the accompanying drawings:—Figure 1 is a perspective view of a casing or holder constructed in accordance with the invention, parts being broken away in order to more clearly illustrate the construction. Fig. 55 2 is a similar view with the case open, show-

ing the manner in which the goods may be withdrawn, without the removal of the entire roll from the holder. Fig. 3 is a sectional plan view of the holder. Fig. 4 is a view similar to Fig. 3 illustrating a slight 60 modification.

Similar numerals of reference are employed to indicate corresponding parts throughout the several figures of the drawings.

65 The casing or holder is provided with a back piece, which in the present case is shown in the form of a strip 10, and said strip may be secured in any suitable position to any support as by bolts 12 and may be arranged either 70 vertically or horizontally, or in any other position. Secured to this strip is a sheet 15 formed of any suitable material, such, for instance, as leather, leatherboard, oilboard, aluminium, or other sheet material, the material being sufficiently flexible to permit its 75 being rolled properly around the fabric or other merchandise to be protected. The central portion of the sheet is secured to the strip, and the ends are arranged to overlap, 80 the extent to which they overlap being controlled, of course, by the bulk of the merchandise and when used for the protection of rolls of fabric, the ends of the sheet will overlap more and more as the diameter of the roll decreases through the sale of the goods.

85 The sheet is held in position around the roll by one or more straps 17, these being preferably provided with suitable take up 90 buckles or hooks forming convenient fastenings which may be readily cast off, and adjusted as the diameter of the holder decreases, so that the holder may be pressed around the goods and hold the same free from wrinkles. In some cases the sheet may be 95 formed in two sections connected together by a hinge 20 at the back strip, as shown, for instance, in Fig. 4, or the sheets may be arranged to inclose packages of non-circular shape as required.

100 In order to support the silk or other article of merchandise when placed in vertical position, a suitable foot piece 22 is secured to the back strip and extends under the lower end of the casing. This foot piece is preferably 105 formed of a pair of overlapping members, so that its area may be gradually reduced as the diameter of the roll decreases. In order to protect the top of the roll from dust, dirt and the like, a disk or other cover, such as 110

26, may be secured to the back strip as by
nails 27.

The device is found of considerable value
in the protection of expensive articles of
5 merchandise, such, for instance, as silk or
other textile fabrics, and will thoroughly pro-
tect the same from exposure, so that the
outer portion of the roll will not be soiled and
rendered unfit for sale. In use, the roll as a
10 whole may be removed from the casing, if
desired, but the casing is preferably formed
of material of sufficient stiffness to retain the
roll while the desired quantity is drawn off,
as shown, for instance, in Fig. 2.

15 I claim:—

1. A merchandise holder comprising a
flexible sheet rolled to form a tubular casing
of variable diameter, adjustable securing
means for maintaining the same at the de-
20 sired diameter, and an exterior rigid support
attached to the sheet and bearing thereon
throughout its length.

2. A merchandise holder comprising a
flexible sheet rolled to form a tube of variable
25 diameter, adjustable securing means for the

same, and a rigid supporting strip disposed
longitudinally of the sheet.

3. A merchandise holder comprising a
flexible sheet rolled to form a tube of variable
diameter, adjustable securing means for the
30 sheet, and a rigid strip secured longitudinally
of the sheet and provided with an attaching
means.

4. A merchandise holder comprising a
foldable casing, a longitudinal strip secured
35 to the casing, and a flexible securing band
encircling the casing and held in place by
said strip.

5. A merchandise holder comprising a
foldable casing, a longitudinal strip attached
40 thereto, and a base and cap secured, respec-
tively, to the extremities of the strip for clos-
ing the ends of the casing.

In testimony that I claim the foregoing as
my own, I have hereto affixed my signature 45
in the presence of two witnesses.

DAVID F. GREENAWALT.
